(57) **CLAIM**

The ornamental design for a lamp as shown and described.

DESCRIPTION

FIG. 1 is a first perspective view of a first embodiment of a lamp showing my design.

FIG. 2 is a second perspective view thereof.

FIG. 3 is a front elevation view thereof.

FIG. 4 is a back elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a first perspective view of a second embodiment of a lamp showing my design.

FIG. 10 is a second perspective view thereof.

FIG. 11 is a front elevation view thereof.

FIG. 12 is a back elevation view thereof.

FIG. 13 is a left side elevation view thereof.

FIG. 14 is a right side elevation view thereof.

FIG. 15 is a top plan view thereof.

FIG. 16 is a bottom plan view thereof.

FIG. 17 is a first perspective view of a third embodiment of a lamp showing my design.

FIG. 18 is a second perspective view thereof.

FIG. 19 is a front elevation view thereof.

FIG. 20 is a back elevation view thereof.

FIG. 21 is a left side elevation view thereof.

FIG. 22 is a right side elevation view thereof.

FIG. 23 is a top plan view thereof.

FIG. 24 is a bottom plan view thereof.

FIG. 25 is a first perspective view of a fourth embodiment of a lamp showing my design.

FIG. 26 is a second perspective view thereof.

FIG. 27 is a front elevation view thereof.

FIG. 28 is a back elevation view thereof.

FIG. 29 is a left side elevation view thereof.

FIG. 30 is a right side elevation view thereof.

FIG. 31 is a top plan view thereof; and,

FIG. 32 is a bottom plan view thereof.

Color forms no part of the present design.

Although usable in other ways, the lamp is intended to be

usable for illumination, e.g., on the ground.
